PUMP OPERATING UNIT

Paul E. Noll, Pasadena, Charles W. Crawford, Los Angeles, T. Dwight Aller, San Gabriel, and Albert R. Rethay, Los Angeles, Calif., assignors, by mesne assignments, to Consolidated Western Steel Corporation, Los Angeles, Calif., a corporation of Delaware

Application May 10, 1946, Serial No. 668,942

7 Claims. (Cl. 60—52)

1

This invention relates to a pump operating unit and has particular reference to a hydraulic power unit which finds particular utility when employed to actuate a reciprocating pump disposed deep within the bore of an oil well.

In the production of petroleum fluids from oil wells which do not flow, it is common practice to employ a reciprocating pump which is located deep within the well bore and which is operated by means of a string of sucker rods extending to the ground surface. The upper or polish rod section of the sucker rod string is ordinarily reciprocated by a pump operating unit consisting of a walking beam, one end of which is connected by a horsehead sling to the polish rod, and the other end of which is connected by a pitman to a rotating crank which is driven by a suitable prime mover, such as an electric motor or internal combustion engine.

Because of the physical limitations imposed by the walking beam construction, the maximum stroke length which may be imparted to the polish rod normally does not exceed six or eight feet, and strokes of about three feet are most common. Since the load on the sucker rod string varies from a maximum during the working stroke to a minimum during the return stroke, the stretching of the sucker rod string may be sufficient in a deep well to reduce the effective pump stroke at the bottom of the well bore to only a few inches. A great deal of power, therefore, is lost and the rate of oil production accordingly is very low. Because the motion of a conventional pump operating unit is substantially simple harmonic motion, an attempt to increase the production rate by operating at a higher frequency may give rise to destructive harmonic vibrations in the sucker rod string. Also, the simple harmonic motion employed with the conventional pump operating units provides a return stroke rate which is approximately equal to the power stroke rate, thus consuming considerable time with the non-productive portion of the operating cycle.

As is well understood in the art of operating deep well pumps, the sudden reversal of movement at the end of the up stroke and down stroke of the sucker rods imposes reversal strains on the sucker rods as the stretch of the sucker rods is either suddenly released or suddenly imposed upon the rods, and it is, therefore, extremely desirable that the rods not only be brought to rest at the end of each stroke and restarted by a gradual deceleration and acceleration, but there should be a pause or dwell in the movement of

2

the rods at the end of each stroke, which will permit the strains in the rods to be relieved. The dwell or pause at the end of the down stroke is additionally desirable when the pump is employed to operate a relatively heavy or viscous oil for the purpose of providing a long interval within which the oil may flow into the inlet of the pump to completely fill the pump chamber prior to the initiation of the next up stroke of the pump.

It is, therefore, an object of this invention to provide a pump operating unit which overcomes the above noted disadvantages by employing a hydraulically operated ram which is connected to the sucker rod string.

It is also an object of this invention to provide a pump operating unit of the character set forth in the preceding paragraph, which includes means for adjusting the stroke length up to values greatly exceeding the maximum stroke obtainable with walking beam types of pump operating units.

It is an additional object of this invention to provide a pump operating unit of the character set forth in the preceding paragraphs which includes means for producing a regulatable relatively rapid motion of the sucker rod string during the non-productive portion of the operating cycle.

It is a still further object of this invention to provide a pump operating unit of the character set forth hereinbefore, which includes means for producing a dwell or pause at each end of the stroke.

It is additionally an object of this invention to provide a pump operating unit of the character referred to which includes means for adjusting the accelerations and decelerations of the sucker rod string.

It is also an object of this invention to provide a pump operating unit of the character set forth in the preceding paragraphs which includes a novel hydraulic control valve for obtaining the modes of operation above mentioned.

It is a still further object of this invention to provide a pump operating unit of the character set forth hereinbefore, which includes a novel counterbalancing device, together with means for limiting the velocity of the moving parts in the event of a failure of the sucker rod string.

It is also an object of this invention to provide a pump operating unit of the character referred to in the preceding paragraphs in which the counter-balancing device is of the compressed gas type and which includes means for automatically

maintaining a predetermined average gas pressure.

It is additionally an object of this invention to provide a pump operating unit of the character referred to which includes means for continuously removing entrapped air or gas from the hydraulic system.

Other objects and advantages of this invention will be apparent from a study of the following specifications read in connection with the accompanying drawings, wherein:

Fig. 1 is a side elevational view illustrating the general form and appearance of the preferred embodiment of this invention;

Fig. 2 is a fragmentary cross-sectional view illustrating the details of construction of the hydraulic ram portion of the unit;

Fig. 3 is a diagrammatic side elevational view of the apparatus shown in Fig. 1 and illustrating the piping employed in the hydraulic power and control circuits, Fig. 3 illustrating the operation of the device during the upstroke of the unit;

Fig. 4 is a cross-sectional view of the main control valve which is used to control the operation of the hydraulic ram portion of the unit, Fig. 4 illustrating the positions occupied by the parts of the valve during the phase of operation which is shown in Fig. 3;

Fig. 5 is a view similar to Fig. 3 but showing the apparatus during the down stroke portion of the operating cycle;

Fig. 6 is a view similar to Fig. 4 but showing the positions occupied by the main control valve parts during the down stroke portion of the operating cycle;

Fig. 7 is a view similar to Figs. 3 and 5 but illustrating a modified form of the invention in which means is provided for producing a pause or dwell at each end of the operating stroke, Fig. 7 showing the piping employed in the hydraulic power and control circuits;

Fig. 8 is a diagrammatic view showing in cross-section the details of construction of a main control valve and an auxiliary control valve employed with the modified form of the invention which is represented in Fig. 7, Fig. 8 illustrating that portion of the operating sequence during which the unit is producing a power stroke;

Fig. 9 is a view similar to Fig. 8 but showing the operation of the apparatus at the time the ram of the unit approaches the upper end of the upstroke;

Fig. 10 is a view similar to Figs. 8 and 9 but illustrating the operation of the apparatus during the pause or dwell which is produced at the top of the upstroke;

Fig. 11 is a view similar to Figs. 8 through 10 but illustrating the sequence of operation during the return or down stroke of the hydraulic ram;

Fig. 12 is a view similar to Figs. 8 through 11 but illustrating the operation at a point near the bottom of the down stroke; and

Fig. 13 is a view similar to Figs. 8 through 12 but illustrating the positions occupied by the parts during the pause or dwell which is produced at the bottom of the down stroke.

Referring to the drawings, there is illustrated in Fig. 1 the preferred embodiment of this invention. In accordance therewith, the pump operating unit assembly indicated generally by the reference character 1 is mounted upon a base frame 2 which may be provided with wheels 3 and 4 and adapted to be raised or lowered into engagement with track members 5 and 6 to facilitate

movement of the unit between an operating position illustrated and a retracted position, giving free working access to a casing head 7 which is used to terminate the upper end of a well casing 8 and flow tubing 9 mounted concentrically therein, through which a polish rod 10 extends, the polish rod 10 comprising the upper section of a string of sucker rods extended down through the well bore to the reciprocating pump which is mounted at the lower end of the flow tubing.

The unit 1 comprises a hydraulic ram mechanism indicated generally by the reference character 11 and comprising an outer cylinder 12 within which is telescopically inserted a ram 13,

15 the ram 13 being movable in a manner to be described hereinafter between a lowermost position such as is illustrated by solid lines in Fig. 1 to an uppermost position such as is illustrated by dotted lines in that figure.

20 The upper end of the ram 13 is mounted by a head member 14 which serves to journal two pairs of sheaves 15 and 16. A double cable 17, anchored as indicated diagrammatically at 18 by a fixed sheave is passed over the sheaves 15 and 16 and downwardly to a cable attachment 19 by means of which the ends of the cables 17 are secured to the polish rod 10. It will be seen that reciprocal motion of the ram 13 between the solid and dotted line positions illustrated in Fig. 1 will effect a reciprocating motion of the polish rod 10; and that by reason of the double reeving employed, the stroke imparted to the polish rod 10 will be twice the distance through which the ram 13 is reciprocated. By this means it is possible to reciprocate the polish rod 10 through a stroke length which greatly exceeds the maximum stroke length which may be obtained with the conventional walking beam type of unit.

The unit 1 includes also a housing or enclosure 20 which serves to house the hydraulic equipment to be described hereinafter which is used to effect a reciprocation of the ram 13.

As is best shown in Fig. 2, the hydraulic ram construction 11 comprises, as stated, the outer cylinder 12 within which the ram 13 is telescopically mounted. The ram 13 preferably comprises a tubular member, to the upper end of which is attached a head 21 to which is attached, as by means of studs and nuts 22, the sheave supporting head 14. The ram 13 is provided with an overall length substantially equal to or somewhat exceeding the length of the outer cylinder 12 and is made with a materially smaller diameter than the inside diameter of the cylinder 12 to define between the ram and cylinder an annular fluid receiving space 23. The lower end of the ram carries an annular piston member 24 which, by means of sealing rings 25, makes a fluid-tight sliding fit with the interior of the cylinder 12. The upper end of the ram 13 is guided by means of a guide member 26 which is secured to a flange 27 carried by the upper end of the cylinder 12 by means of bolts 28. The upper end of member 26 forms a stuffing box 29 in which packing material 30 and a gland member 31 cooperate to establish a fluid seal between the ram 13 and the upper end of the cylinder 12.

The lower end of the cylinder 12 carries a flange member 33 to which is secured, as by means of bolts 34, a lower closure member 35. The lower closure member 35 serves to support a central tubular member 36 which is secured at its lower end to the closure 35 and which is, at its upper end, secured as by means of a flange 37 and bolts 38 to a stationary piston 39 which, by reason of

associated sealing rings 40, makes a fluid-tight sliding seal with the inner surface of the tubular ram 13. The tubular conduit 36 serves to define within the cylinder 12 a fluid receiving space 41 disposed below the ram piston 24. With the structure thus far described, it will be realized that fluid under pressure injected into the space 41 will cause the ram 13 to rise within the cylinder 12, whereas the injection of fluid under pressure into the annular space 23 above the ram piston 24 will cause the ram 13 to telescopically descend within the outer cylinder 12.

The manner in which this reciprocating motion of the ram 13 is obtained may be seen by having reference to Fig. 3 wherein the remainder of the equipment and the piping is illustrated in diagrammatic form. As is shown in Fig. 3, there is provided within the housing 20 a storage tank 42 for holding a supply of hydraulic fluid used in the operation of the system. An intake line 43 extends from the storage tank 42 to the inlet of a high pressure positive displacement pump 44, the discharge of which is connected by a conduit 45 to the pressure inlet port of a main control valve 46 which may be described generally as of the four-way type, but it will be described in detail hereinafter.

From the four-way valve 46 a conduit 47 leads to the annular space 41 beneath the ram piston 24 and another conduit 48 leads to the annular space 23 above the ram piston 24. Conduits 49 and 50 joining a conduit 51 lead from the four-way valve 46 to the storage reservoir 42.

The piping thus far described provides for the drawing of fluid from the storage tank 42 and supplying that fluid under pressure to the four-way valve 46. Depending upon the operative position of the valve 46, the fluid is supplied either to the cylinder 12 above or below the ram piston 24 to lower or raise the ram piston and the fluid displaced from the opposite side of the piston by the movement thereof is returned to the four-way valve 46 and by means of the conduit 51 to the storage tank 42. As stated, the pump 44 is preferably of the positive displacement type and, therefore, a shunt line 52 is connected between the conduit 45 and the reservoir 42 through a pressure relief valve 53, so that excess fluid transmitted by the pump 44 may be returned directly to the storage tank 42 while a substantially constant operating pressure on the high pressure side of the valve 46 is maintained by the normal operation of the pressure relief valve 53.

The main control valve 46 is hydraulically controlled by means of a four-way pilot valve 54. The valve 54 is connected by a conduit 55 to the conduit 45 through a pressure reducing valve 56. A conduit 57 connects the pilot valve 54 with the storage tank 42 while conduits 58 and 59 connect the pilot valve 54 with the main control valve 46. In conduit 58 is located a throttling valve 60 which is by-passed by a check valve 61 while a similar arrangement, including a throttling valve 62 and check valve 63, is employed in connection with the conduit 59.

The pilot valve 54 may be of any suitable conventional construction which includes an operating lever 64 so arranged that in one position of the lever 64 the conduit 55 will be connected to the conduit 59, while the conduit 58 is connected to the conduit 57 and such that in a second position of the lever 64, the conduit 55 will be connected to the conduit 58 and the conduit 59 will be connected to the conduit 57. The operating

lever 64 is disposed in a position to be engaged by actuating members 65 and 66 mounted for adjustable movement along a control rod or cable 67 which is preferably attached to the head member 14 to reproduce the reciprocating motion of the ram 13. The actuating members 65 and 66 are so positioned that the lever 64 is engaged by the actuating member 66 and moved from one position to another as ram 13 nears the upper end of its up stroke, and in such position that the actuating member 65 will engage the operating member 64 and move the valve back to its former position as ram 13 nears the bottom end of its down stroke.

The construction of the main control valve 46 is shown in Fig. 4, in which figure the valve parts are shown as occupying positions corresponding to the phase of operation which is illustrated diagrammatically in Fig. 3, in which the ram 13 has just started its up stroke. As is shown in Fig. 4, the main control valve 46 comprises a body member 68 within which is mounted a cylinder 69. The cylinder 69 is made considerably smaller than the housing 68 to define between the cylinder 69 and the housing 68 an annular space 70.

The radial flanges or ribs welded or otherwise suitably secured to the exterior of the cylinder 69 and engaging the inner surface of the housing 68 serve to divide the annular space 70 into a number of chambers including a fluid inlet chamber 71 to which the conduit 45 is connected as by means of a connecting member 72, a bottom cylinder chamber 73 to which the conduit 47 is connected as by means of a connection 74, a top cylinder chamber 75 to which the conduit 48 is connected as by means of a connection 76 and fluid return chambers 77 and 78 situated at the ends of the housing member 68 and to which the conduits 49 and 50 are respectively connected as by means of connection members 79 and 80.

The chamber portions 77 and 78 are communicated with the interior of the cylinder 69 through the open ends thereof and the chambers 71, 73 and 75 are communicated with the interior of the cylinder 69 by means of fluid ports extending through the wall thereof.

There is reciprocally mounted within the cylinder 69 a tubular valve spool 81 characterized by end lands 82 and 83 between which are disposed intermediate lands 84 and 85. The annular space between lands 82 and 85 is communicated with the interior of the tubular spool 81 by means of radial ports through the wall thereof as is the annular space between the lands 83 and 84.

The ends of the housing 68 are preferably flanged as at 86 and 87 to permit a flanged connection thereto of operating cylinders 88 and 89. Operating pistons 90 and 91 are slidably mounted within the cylinders 88 and 89 and are connected to the valve spool 81 as by means of connecting rods 92 and 93. The outer ends of the cylinders 88 and 89 are closed respectively by caps 94 and 95 which include means for attachment of conduits 96 and 97, the conduit 96 being connected to the downstream side of the valves 62 and 63 and the conduit 97 being connected to the downstream side of the valves 60 and 61. It will be appreciated that the admission of fluid under pressure through the conduit 96 to the interior of the cylinder 88 will move the piston 90 thereof downwardly as viewed in Fig. 4 to shift the valve spool 81 to the position shown in that figure.

Conversely, the position of the valve may be reversed by supplying fluid under pressure through the conduit 97.

In Fig. 3 the various parts are shown in the positions occupied at the beginning of an up stroke. Near the end of the down stroke the actuating member 65 engaged the operating member 64 of the valve 54 and moved the same to a position connecting the conduit 55 to the conduit 59. Fluid under pressure from the pump discharge 45 and through the pressure reducing valve 56 is thus supplied to the conduit 59 and through the check valve 63 and conduit 96 to the cylinder 88 which was thereby moved to the position shown in Fig. 4. In that position hydraulic fluid supplied through the conduit 45 is communicated to chamber 71 and through the ports in cylinder 69 to the annular space around valve spool 81 and between lands 84 and 85, and from there through other ports in the cylinder 69 to the chamber 73 connecting with the conduit 47.

Fluid flow is thus established between conduits 45 and 47 to supply fluid under pressure to the space 41 within the cylinder 12 beneath the ram piston 24. The resulting upward movement of the ram 13 displaces fluid from the annular space 23 which is conveyed through conduit 48 to the chamber 75 and through the corresponding cylinder wall ports to the annular space between lands 83 and 84. From this space the fluid flows through the port in the wall of the tubular valve spool to the interior of the spool from where it is free to flow lengthwise into the end chambers 77 and 78. These chambers are connected to the conduits 49 and 50 so that the fluid displaced from the annular space 23 within the cylinder 12 is returned through conduit 51 to the storage tank 42. The ram 13 continues to rise until the lower actuating member 68 engages the operating member 64 to trip the pilot valve 54 to its alternate position interconnecting conduits 55 and 58. This supplies fluid under pressure through check valve 61 and conduit 97 to the interior of the cylinder 88, causing the piston 91 therein to move upwardly from that shown in Fig. 4, to its alternate position which is illustrated in Fig. 6. In so doing, the fluid contained within the cylinder 88 is displaced by the accompanying upward movement of the piston 90 and is accordingly returned through conduit 96 and throttling valve 62 to conduit 59 which is connected by the valve 54 to the return line 57 leading to the storage tank 42.

This flow of fluid from the cylinder 88 is all through the valve 62 since the check valve 63 is opposed to the reverse flow of fluid. Therefore, by adjusting the throttling valve 62, the rate at which fluid is displaced from the cylinder 88 may be adjusted so that the valve 46 may be caused to shift from the position shown in Fig. 4 to that shown in Fig. 6 at a suitably adjusted relatively slow rate.

As will be seen from a study of Figs. 4 and 5 and a comparison of Figs. 3 and 5, the shifting of the valve 46 from the position shown in Fig. 4 to that shown in Fig. 6 serves to connect the high pressure supply represented by conduit 45 to the conduit 48 instead of to the conduit 47, and serves to connect the conduit 47 to the return line 51 instead of the conduit 48. This, of course, supplies fluid under pressure to the upper side of the ram piston to cause the ram to descend. However, since the valve spool 81 is slowly moved between the two positions, the ports traversed by the lands 82-85 are gradually closed to uniformly

decelerate the upward movement of the ram 13 and the other ports are gradually opened to uniformly accelerate the downward motion of the ram 13. Since the acceleration and deceleration is dependent entirely upon the rate of movement of the valve spool 81, it is seen that the throttling valve 62 provides a complete adjustable control over the deceleration and acceleration of the ram piston at the upper end of the ram stroke.

In a similar way the shifting of the valve 46 from the position shown in Fig. 6 to that shown in Fig. 4 occurring near the end of the down stroke of the ram, is accompanied by a return of fluid through the throttling valve 60 which may be adjusted to regulate, as desired, the deceleration and acceleration of the ram at the end of the down stroke in the same way as has just been described in connection with the throttling valve 62.

During the above described sequence of operations the ram 13 is reciprocated to thereby reciprocate the polish rod 10 through the driving connection afforded by the cable 17. It will be seen that during the up stroke, the load applied to the cable 17 is the weight of the sucker rod string, plus the weight of the column of oil lifted; whereas during the down stroke, the weight of the column of fluid is carried by the foot valve of the oil well pump so that there is applied to the cable 17 only the weight of the sucker rod string. Accordingly, to avoid an undesirable condition of varying load on the prime mover, it is preferred to apply an upward acting counterbalancing force to balance the weight of the sucker rod string, plus approximately one-half of the weight of the column of fluid contained within the flow tubing.

This counterbalancing force is preferably applied to the interior of the ram 13 by means of an incompressible fluid such as oil which fills a space 98 comprising the interior of the tubular ram 13 and which communicates with the interior of the central tubular member 36, as is best shown in Figs. 2 and 3. The tubular member 36 is connected to a conduit 99 by means of a flanged attachment 100 which is secured as by means of bolts 101 to the lower closure member 35. The conduit 99 is connected, as shown in Fig. 3, to the interior of an annular pressure chamber 102 which, by preference, surrounds the outer cylinder 12 and is secured thereto as by means of welding 103. The pressure chamber 102 is partially filled with incompressible fluid while the upper portion is filled with gas under pressure. The gas contained within the upper portion of the chamber 102 is introduced at a pressure sufficient to cause the incompressible fluid conducted to the interior of the ram 13 through the conduits 99 and 36 to exert an upward force on the ram 13 equal to the desired counterbalancing force to be exerted.

In order to compensate for the possible loss of gas from the upper portion of the pressure chamber 102, there is provided a make-up pump indicated generally at 104 in Fig. 3. The pump 104 preferably comprises a cylinder member 105 which is bored as at 106 to receive a piston 107. To the piston 107 there is secured a piston extension 108 which is adapted to reciprocate within a gas compressing bore 109. An intake line 110 is adapted to be connected to a suitable source of gas or in the event air is used as the gas to fill the pressure chamber 102, the end of the conduit 110 is merely communicated with the atmosphere.

The conduit 110 communicates through a check valve 111 to the interior of the gas compressing cylinder bore 109. A discharge line 112

also communicates with the interior of the bore 109 and is passed through a check valve 113. From the check valve 113 a conduit 114 leads to the interior of the pressure chamber 102, as shown at 115. With the construction thus far described, it will be seen that reciprocation of the piston extension 108 will draw gas into the bore 109 during the down stroke of the piston and will during the up stroke thereof deliver said gas under pressure to the interior of the pressure chamber 102.

The piston extension 108 is reciprocated by the application of fluid pressure alternately to opposite ends of the cylinder 106. For this purpose conduits 116 and 117 are connected between the bottom of the cylinder 106 and the line 47 which leads from the valve 46 to the lower end of the main hydraulic ram cylinder. Similarly, conduits 118 and 119 lead from the upper end of the cylinder 106 to the line 48 connecting the main control valve 46 with the upper end of the main hydraulic cylinder. Since fluid under pressure is alternately supplied to and returned from each of the lines 47 and 48 by the action of the main control valve 46, it will be seen that the piston 107 and piston extension 108 will be reciprocated in synchronism with the reciprocation of the ram 13 and that as a result thereof, air or other suitable gas will be continually forced into the pressure chamber 102.

In order that the pressure within the chamber 102 may be held at a proper and regulated value, a manually adjustable pressure relief valve 120 is connected to the interior of the chamber 102 as by means of a conduit 121. In normal operation, the gas make-up pump 104 supplies gas at a rate in excess of the leakage requirements so that the excess may be discharged through the pressure relief valve 120. This valve then operates to maintain a substantially constant average pressure within the interior of the pressure chamber 102.

In the event the sucker rod string should break, the load which is applied to the ram 13 would be instantly materially reduced, with the result that in the absence of some means for arresting or retarding upward movement of the ram, the counterbalancing force exerted by the gas compressed within the pressure chamber 102 would cause the ram 13 to rise at a destructive velocity.

Accordingly, the present invention includes a velocity limiting valve 122 (see Fig. 2) which comprises a disc-like valve member 123 mounted upon a stem 124 which is slidably mounted in a guide 125 carried by a spider 126 secured to the conduit 99. A spring 127 is employed to normally urge the valve 123 to a retracted position, such as that shown in Fig. 2, in which the valve member 123 is spaced from a seat 128 which it is adapted to engage in its upper position. A plurality of apertures or ports 129 are provided in the valve disc 123 so that in its upper position, the flow of fluid through the conduits 99 and 36 will not be completely arrested but merely throttled.

The pressure of the spring 127 is so adjusted as to maintain the valve 123 in the normal position shown in Fig. 2 during normal operation of the apparatus. However, should the sucker rod string break or the downward load imposed upon the ram 13 be for any other reason immediately relieved, then flow of fluid through the conduit 99 and past the valve 123 will rise to a value mate-

rially exceeding the normal rate of flow. The hydraulic friction drag exerted on the valve 123 will then overcome the force of the spring 127 and move the valve 123 to its closed position so that thereafter fluid transferred from the conduit 99 to the conduit 36 must be passed through the small holes 129 in the valve disc 123. This throttling action serves to limit to a safe value the rate of upward movement of the ram 13.

10 In order for the above-described counterbalancing action to take place continuously and over long periods of operation, it is necessary that any gas which may move into the space 98 be removed therefrom to prevent an accumulation 15 of gas in the upper end of the interior of the ram 13. To this end there is provided a scavenging pump indicated generally by the reference character 130 which comprises a cylinder member 131 mounted upon a lower head member 132 which is in turn carried by uprights 133 secured to the stationary piston 39. A piston 134 is reciprocally mounted within the cylinder 131 and carries a tubular piston rod 135 which extends through an intake check valve 136 to an inlet 20 conduit 137 which is terminated in a position to be engaged by an upper cap member 138 (serving as a closure for the interior of the ram 13) during the last few inches of downward travel of the ram 13. This serves to move the piston 134 25 downwardly within the cylinder 131. When the ram 13 is moved upwardly, the piston 134 is simultaneously moved upwardly by means of a compression spring 139 which surrounds the cylinder 131 and is engaged between the lower 30 head 132 and a disc-like member 140 secured to the piston rod 135. The head member 132 is chambered as shown in Fig. 2 to house a discharge check valve 141 which communicates with a conduit 142 which is connected as shown 35 in Fig. 3 to an external conduit 143 connecting with the conduit 115.

It will be seen that the structure just described comprises a small pump mounted within the interior of the ram 13 and which operates to take in fluid or gas from the extreme upper end of the space 98 and discharge the same through the conduits 142 and 143 to the conduit 115 by which it is returned to the interior of the pressure chamber 102. Thus, any tendency for gas 45 or air to collect in the space 98 is completely offset by the removal of that gas as fast as it accumulates.

As hereinbefore stated, it is desirable to provide in a control system of the character described a means for causing the ram to pause for a predetermined length of time at each end of the stroke. There is accordingly illustrated in Figs. 7 through 13 an alternative embodiment of the present invention which includes the necessary control apparatus for providing such a pause or "dwell" at each end of the operating stroke. As will be apparent from Fig. 7, the apparatus employed is substantially identical to that which has been described hereinbefore except for the substitution in place of the valve 46 of a different main control valve which is indicated generally in Fig. 7 by the reference character 144 and the association therewith of a dwell cylinder 145. Also, there is interposed between the conduit 45 leading from the pump 44 and the pressure inlet port of the four-way control valve 144 a resistance valve 189, the purpose of which will be described hereinafter.

As before, the main hydraulic power supply 75 connections comprise conduits 47 and 48 leading

from the four-way control valve 144 respectively to the lower and upper ends of the hydraulic cylinder 12 and return lines 49, 50 and 51 leading from the four-way control valve 144 to the reservoir 42. As in the previously described modification, the pilot control valve 54 is connected by the conduit 55 and pressure regulating valve 56 to the conduit 45 and is provided with the return line 57 leading to the reservoir 42. In the alternate positions of the pilot control valve 54, it is adapted, as before, to connect the conduit 55 to conduits 58 and 59, which conduits lead to the main control valve 144 and the associated apparatus to be described hereinafter. The valve 54 is shifted between its two operating positions by means of the operating member 67 and the valve control lever 64.

In Fig. 8 there is illustrated the construction of the four-way control valve 144 and the construction of the dwell cylinder 145. There is also shown diagrammatically the piping which interconnects these two valves with the pilot control valve 54. The main control valve 144 is substantially identical to the control valve 45 hereinbefore described, the principal difference residing in the construction of the valve spool 81A and the operating cylinders 88, 89 and the pistons 90, 91 therefor.

As will be seen in Fig. 8, at one end of each of the cylinders 88 and 89 there are mounted sliding sleeves 146 and 147 which make sealing engagements piston-wise with the walls of the cylinders 88 and 89 and which in turn slidably receives the inner end of the pistons 90, 91. Mechanical connection between the sleeves 146 and 147 and the associated pistons is effected by means of annular members 148 which are secured to the outer ends of the sleeves 146 and 147 and which flange inwardly behind the enlarged end of the spool pistons which are received within the sleeves. By inspection of Fig. 8, it will be seen that an inward movement of either sleeve 146 or 147 will mechanically drag the pistons 90 or 91 therewith to a midposition, but that the pistons are each permitted additional inward movement to an extreme inner position. It will also be seen that upon movement of either piston to its extreme outer position as, for example, that occupied by the piston 90 in Fig. 8, the corresponding sleeve will be mechanically moved to its outermost position.

In Fig. 8 the parts are shown in the position they occupy during an upward stroke of the ram 13. It will be seen that fluid under pressure supplied to the conduit 45 is conveyed to the conduit 47 through the valve 144 and to the lower end of the hydraulic cylinder 12. Fluid returned from the upper end of the hydraulic cylinder 12 is returned through conduit 48 through the valve 144 to conduits 49 and 50 and from there to the conduit 51 and storage tank 42.

During this time pilot control pressure derived from the conduit 55 is conveyed through the control valve 54 and conduit 58 to a conduit 149 communicating with the interior of the cylinder 89. In this part of the cycle of operations the piston 91 and sleeve 147 associated therewith occupy the position shown in Fig. 8 so that fluid may flow from conduit 149 through the interior of the cylinder 91 to a conduit 150 which is connected through a check valve 151 to the right-hand end of the dwell cylinder 145 which comprises an elongated hydraulic cylinder 152 with-

in which is reciprocally mounted a spool-shaped piston member 153.

The piston member 153 now occupies the extreme left-hand position, in which position the right-hand end of the spool 153 lies between a centrally located inlet conduit 154 and a conduit connection 155. Therefore, in the position shown, fluid flowing into the interior of the cylinder 152 through the check valve 151 may flow out the conduit 155 and through a check valve 156 to a conduit 157 which communicates with the right-hand end of the cylinder 89 to thereby urge the piston 91 to the left to the position shown in Fig. 8.

As the ram 13 approaches the upper end of the up stroke, the valve 54 is shifted to its alternate position to supply control pressure from the source conduit 55 to the conduit 59 and at the same time to release pressure from conduit 58 through conduit 57 to the storage tank. As is shown in Fig. 9, the supply control pressure is conveyed through a conduit 158 to the interior of the cylinder 88 at a point to the left of sleeve 146, as viewed in Fig. 9. This pressure is effective to cause the sleeve 146 and piston 90 to move to the right as viewed in Fig. 9 because the area of the end of the sleeve 146 is greater than the area of the left-hand end of the piston 90. The resulting movement of the piston 90 to the right moves the main control valve 144 toward a neutral position. As this motion takes place, fluid to fill the left-hand end of the cylinder 88 is drawn through conduits 159 and 160, check valve 161 and conduit 162 communicating with the interior of the dwell cylinder 152. Because of the then position of the dwell piston 153, the conduit 162 is communicated with the inlet conduit 154 so that fluid may be drawn in through that conduit through a check valve 163 and a conduit 164 which is in communication with the storage tank 42. Likewise, fluid displaced from the interior of the cylinder 89 by movement of the piston 91 to the right is discharged through the conduit 157. It is prevented from flowing into the conduit 155 by reason of the check valve 156 and is, therefore, forced to flow through a conduit 165, throttling valve 166 and check valve 167 to the conduit 58 which is connected through the control valve 54 to the conduit 57 which returns to the storage tank 42.

The described movement of the piston 90 to the right continues until the spool 81A of main control valve 144 reaches a neutral position, at which time the sleeve 146 associated with the piston 90 has seated against stop 146A and has uncovered a port leading to a conduit 168 which directs the pressure fluid through check valve 169 and conduit 170 to the left-hand end of dwell cylinder 152.

As is shown in Fig. 10, the neutral position of the spool 81A in main valve 144 is such that the pressure supply line 45 is communicated directly with the two return lines 49 and 50 while the two cylinder lines 47 and 48 are closed off. In this position of the valve, therefore, movement of the ram 13 is arrested and the ram remains stationary so long as the spool 81A remains in the neutral position.

The rate of movement of the main valve from the position shown in Fig. 9 to that shown in Fig. 10 is controlled for the purpose of controlling the rate of deceleration of the ram 13 by adjustment of the valve 166 which regulates the rate at which fluid may be displaced from the cylinder 89 by the movement of the piston 91 therein. When

the valve 144 reaches a neutral position as shown in Fig. 10, the uncovering of the port leading to the conduit 168 intercommunicates the conduits 158 and 168 so that fluid under pressure delivered from the control valve 54 through conduit 59 may flow through the conduit 168, a check valve 169 and conduit 170 to the left-hand end of the dwell cylinder 152. The pressure thus applied to the left-hand end of the piston 153 causes said piston to move to the right within the cylinder 152 toward the opposite end of the cylinder.

During the first part of this motion the right-hand end of the piston 153 closes the port leading to the conduit 155 so that fluid contained within the cylinder 152 to the right of the piston 153 will be displaced therefrom through conduit 171, throttling valve 172 and conduit 159 to the interior of the cylinder 89. By virtue of the sliding interconnection of the piston 91 with the sleeve 147, the movement of the piston 91 to the right to the midposition did not produce any motion of the sleeve 147 so that a fluid connection between conduits 150 and 149 remains through the interior of the cylinder 89. Fluid thus passed into the conduit 149 is conveyed by conduit 58 to the control valve 54 and thence by way of conduit 57 to the storage tank 42.

The flow of the displaced fluid just described is forced through the throttling valve 172 by reason of the flow being in a direction reverse to that permitted by the check valve 151. Thus adjustment of the throttling valve 172 may be employed to control the rate of travel of the piston 153 within the cylinder 152 and, therefore, the length of time required for the piston to move from the position shown in Fig. 10 to that shown in Fig. 11. When the piston 153 finally reaches the right-hand end of the cylinder 152 as is shown in Fig. 11, the left-hand end of the piston 153 uncovers the port which communicates with the conduit 162. This establishes a communication between the conduits 170 and 162 so that fluid flowing into the cylinder 152 through the conduit 170 may now flow through conduit 162, check valve 161 and conduits 160 and 159 to the interior of the cylinder 88 at the left-hand end of the piston 90. This application of pressure to the left-hand end of the piston 90 causes the piston to move to the right to shift the spool 81A of main control valve 144 to its other operating position in which fluid under pressure supplied through conduit 45 is conveyed to the upper end of the hydraulic cylinder through conduit 48 while fluid returned from the lower end of the hydraulic cylinder through conduit 47 is conveyed by means of conduits 49, 50 and 51 to the storage tank 42, thus starting the descent of the ram on its down stroke. During movement of the valve spool 81A from the position shown in Fig. 10 to that shown in Fig. 11, fluid is again displaced from the cylinder 89 through conduits 157, 165 and valves 166 and 167 as was described in connection with Fig. 9. As before, the valve 166 in throttling this flow regulates the rate of travel of the valve spool 81A to the position shown in Fig. 11.

The valves remain in the position shown in Fig. 11 until the ram 13 approaches the lower limit of its down stroke, at which time the pilot control valve 54 is tripped to its first position connecting the pressure source line 55 to the conduit 58 and connecting the conduit 59 to the return line 57 leading to the storage tank 42 as shown in Fig. 12. In this position fluid under pressure is conveyed through conduits 58 and 149 to the interior of the cylinder 89 to act on the

sleeve 147 and move that sleeve and the piston 91 to the left, as viewed in Fig. 12, to move the spool 81A of main control valve 144 from a position shown in Fig. 12 to a neutral position, such as is shown in Fig. 13, in which position conduits 47 and 48 leading to the hydraulic cylinder are cut off and flow is established between the pressure supply conduit 45 and the return conduits 49 and 50.

- 10 During movement of the spool 81A of main valve 144 to the left, fluid displaced from the cylinder 88 by movement of the piston 90 therein as conveyed through conduit 159, conduit 173, throttling valve 174 and check valve 175 to conduit 59 which is connected through the control valve 54 to the return conduit 57 leading to the storage tank 42. Flow of fluid from the conduit 159 through conduit 160 is prevented by the check valve 161. The rate of movement of the spool 81A to the left is controlled by regulation of the throttling valve 174.

When the main valve reaches a neutral position as is shown in Fig. 13 communication is established between conduits 149 and 150 to supply fluid under pressure through check valve 151 to the right-hand end of the dwell cylinder 152 to cause the piston 153 thereof to move to the left from the position shown in Fig. 13 to that shown in Fig. 8. During this movement fluid which is displaced by the movement of the piston 153 from the left-hand end of the cylinder 152 is conveyed through conduits 170, 176, throttling valve 177, conduit 178, conduit 168 through the cylinder 88 and by way of conduits 158, 59 and control valve 54 through conduit 57 to the storage tank 42. The check valve 169 forces the fluid to flow through the throttling valve 177, which may be used to regulate the rate of travel of the piston 153 to the left within the cylinder 152 and, therefore, determine the length of time the ram 13 remains stationary at its lowermost position. When finally the piston 153 reaches the extreme left-hand position in moving from the position shown in Fig. 13 to that shown in Fig. 8 communication is established as shown in Fig. 8 between conduits 150 and 155 so that fluid may flow through check valve 156 and conduit 157 to the right-hand end of the cylinder 89 and cause movement of the main valve 144 to the left to the position shown in Fig. 8, in which position hydraulic fluid is supplied to the main cylinder 12 in such a manner as to cause the ram 13 to rise therein.

As before, fluid displaced by movement of the piston 90 will be returned through conduits 159 and 173 and through the throttling valve 174 so that the rate of movement of the main valve is subject to control to thereby regulate the acceleration of the ram in the upward direction. As the ram nears, the upper limit of its upward stroke, the above-described cycle of operation is repeated.

Reference has been made hereinbefore to the resistance valve 180. This valve is connected, as shown in Fig. 7, and arranged to be operated by a control connection 179, by means of which pressure existing in the pressure supply line ahead of main valve 144 is applied to overcome a spring in valve 180 and hold the valve open. It will be seen that during the neutral position of the main valve 144, as is shown in Figs. 10 and 13, the hydraulic power fluid supplied to the valve 144 is returned directly to the storage tank 42 against little, if any, resistance. When this occurs, the spring in valve 180 partially closes the valve to maintain 75 within the conduit 45 a pressure sufficient to sup-

ply through the conduit 55 adequate operating pressure for operating the control apparatus as above-described.

It will be noted that in the operation of reciprocating deep well pumps, the sucker rods are substantially relieved of all load during the down stroke and hence the rods may be moved through the down stroke at a much more rapid rate than would be permissible during the up stroke of the pump. This pump operating unit is particularly adapted for this type of operation by virtue of the construction of the double acting hydraulic ram described herein.

It will be observed that the piston 24 has a considerably greater area exposed to the fluids at its lower end than at its upper end and thus, the pump 44 is required to deliver a considerably greater quantity of fluid during the up stroke of the ram than is required to be delivered during the down stroke. By reason of this construction, the operation of the pump 44 as a constant volume delivery pump will automatically produce a much more rapid down stroke than up stroke of the ram and consequently a similar difference in the speed of movement of the sucker rods.

By referring particularly to Fig. 5, it will be observed that during the down stroke of the ram piston 24, the pump 44 delivers fluid through the conduit 48 to the space 23, and it will also be observed that the conduit 48 which connects with the conduit 48 is coupled to the tank 42 with a valve 200 interposed in the conduit 48. Hence, the rate of speed on the down stroke may be regulated by controlling valve 200. If valve 200 is opened slightly, a portion of the fluid delivered by the pump 44 will by-pass through the conduit 48 back to the tank 44, while the remainder of the fluid delivered by the pump 44 will be delivered to the annular space 23. Hence, as the valve 200 is moved to progressively greater open positions, the volume of fluid which will be delivered to the annular space 23 will be progressively diminished and the down stroke of the ram will be progressively slower and slower.

From the foregoing, it will be observed that the above-described invention comprises a pump operating unit superior in many ways to pumping units of conventional form. Attention is directed particularly to the employment of a double-acting hydraulic ram as the means for applying reciprocating power to the sucker rod string and to the control mechanism which has been described hereinbefore for controlling the operation of the ram.

Attention is directed particularly to the provision of the throttling valves for adjusting the acceleration rates at each end of the stroke, and it is to be particularly noted that with the apparatus as described herein, the acceleration rate at the upper end of the stroke may be adjusted independently of the adjustment of the acceleration rate at the bottom end of the stroke.

It will be noted that there has also been provided a control mechanism for causing the ram to remain stationary for a predetermined length of time at both ends of the stroke and that provision has been made for separately and independently adjusting the duration of the inactive periods.

The provision of the gas pressure counterbalancing system, together with the automatic safety, scavenging and make-up devices therefor permit substantial savings in the power required to produce oil from a given well at a given rate.

While there has been shown and described the

preferred embodiment of the present invention, the same is not to be limited to any of the details of construction shown or described herein, except as defined in the appended claims.

What is claimed as new is:

1. In a pumping unit, the combination of: a double-acting hydraulic ram including a ram member reciprocal in a cylinder, a source of fluid under pressure, and a valve movable between two alternate positions connecting said source respectively to opposite ends of said cylinder to reciprocate said ram member through a predetermined stroke; hydraulic means operable to move said valve between said alternate positions; control means coupled to said hydraulic means and responsive to arrival of said ram member at points near the ends of said stroke for operating said hydraulic means; and means cooperating with said hydraulic means for arresting movement of said valve for a predetermined time substantially midway between said alternate positions to thereby hold said ram member stationary for said predetermined time at the ends of said stroke.

2. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said inner cylinder to reciprocate said ram member; means connecting said ram member to said sucker rod string to reciprocate said string in response to reciprocation of said ram member; a pressure chamber containing an expandable fluid under pressure; and a tube extending through said stationary piston for connecting said pressure chamber to the other end of said inner cylinder to thereby oppose the force exerted by said sucker rod string on said ram member.

3. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said inner cylinder to reciprocate said ram member; means connecting said ram member to said sucker rod string to reciprocate said string in response to reciprocation of said ram member; an annular pressure chamber surrounding said outer cylinder and containing an expandable fluid under pressure; and a tube extending through said stationary piston for connecting said pressure chamber to the other end of said inner cylinder to thereby oppose the force exerted by said sucker rod string on said ram member.

4. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said

inner cylinder to reciprocate said ram member; means connecting said ram member to said sucker rod string to reciprocate said string in response to reciprocation of said ram member; a pressure chamber containing an expansible fluid under pressure; conduit means extending through said stationary piston for connecting said pressure chamber to the other end of said inner cylinder to thereby oppose the force exerted by said sucker rod string on said ram member; and a flow responsive valve in said conduit for partially closing off said conduit when the rate of flow therethrough reaches a predetermined maximum rate.

5. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said inner cylinder to reciprocate said ram member; means connecting said ram member to said sucker rod string to reciprocate said string in response to reciprocation of said ram member; a pressure chamber containing an expansible fluid under pressure; conduit means extending through said stationary piston for connecting said pressure chamber to the other end of said inner cylinder to thereby oppose the force exerted by said sucker rod string on said ram member; a valve member in said conduit movable from a normally open position to a position partially closing off said conduit, said motion being in the same direction as the flow of fluid therethrough during an upward motion of said sucker rod string; and spring means normally urging said valve toward said normally open position.

6. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said inner cylinder to reciprocate said ram member; means connecting said ram member to said sucker rod string to reciprocate said string in response to reciprocation of said ram member; a pressure chamber containing an expansible fluid under pressure and a heavier incompressible fluid; a tube extending through said stationary piston for connecting the bottom of said pressure chamber to the other end of said inner cylinder to thereby transmit through said incompressible fluid the pressure exerted by said

expansible fluid and apply to said ram member a force opposing the force exerted thereon by said sucker rod string; a pump in the upper end of said inner cylinder operable to pump fluid from the extreme upper end of said inner cylinder to the upper portion of said pressure chamber; and means responsive to reciprocation of said ram member for operating said pump.

7. In a pumping unit for reciprocating a sucker rod string extended to a reciprocating pump located in a well bore, the combination of: a double-acting hydraulic ram comprising an outer cylinder, a piston reciprocal in said cylinder, a tubular ram member secured to said piston and defining an inner cylinder, a stationary piston fitted into said inner cylinder, and means for supplying hydraulic fluid under pressure alternately to opposite ends of said outer cylinder and to one end of said inner cylinder to reciprocate said ram member; means connecting said ram member to said sucker rod string to reciprocate said string in response to reciprocation of said ram member; a pressure chamber containing an expansible fluid under pressure; a tube extending through said stationary piston for connecting said pressure chamber to the other end of said inner cylinder to thereby oppose the force exerted by said sucker rod string on said ram member; pump means operable simultaneously with the reciprocation of said ram member to pump expansible fluid into said pressure chamber; and a pressure relief valve on said pressure chamber for limiting the pressure of fluid therein to a predetermined maximum value.
